POWDER DISPENSER

Leslie D. Whitney, San Francisco, Calif.

Application May 7, 1935, Serial No. 20,169

4 Claims. (Cl. 221—61)

My invention relates in general to receptacles for dispensing powder which by reason of its nature and use requires a modicum of the receptacle content.

5 In particular, it concerns such dispensing receptacles as are adapted for hand use, the discharge of the fluent solid being controlled by one or more relatively small or contracted apertures. Such receptacles, for example, are hand shakers 10 for various powders, salt, pepper, talcum, tooth powder, insect powder, and many other fluent solids.

Though my invention is not essentially confined to glass containers, still, for several reasons which 15 I shall hereinafter set forth, it is structurally adapted for glass bottles, in which connection it is my present opinion that its best use lies.

The object of my invention is to provide for 20 such containers, particularly glass bottles, without impairment of their customary neat and attractive appearance, a simple, effective and substantially unnoticeable dispensing device which is readily and securely fitted subsequent to the original free filling of the bottle, and which by reason 25 of being easily removable may restore the bottle to its original freedom of access for refilling or for any other subsequent use, if such be desired.

To this end, my invention consists in the novel 30 construction, arrangement and combination of parts hereinafter fully described, it being understood that changes and modifications may be made without departing from the spirit of the invention within the scope of the claims hereunto appended.

35 In the accompanying drawing, Fig. 1 is an elevation of a glass bottle showing its powder content and its typical flat top cap illustrative of customary appearance but not disclosing the discharge control which is concealed within the bottle neck.

Fig. 2 is a longitudinal section of the bottle, disclosing the complete dispensing device in one position with respect to its ends.

45 Fig. 3 is a similar section, disclosing said dispensing device upside down with respect to its position in Fig. 2.

Fig. 4 is a top plan, enlarged, the cap being removed.

50 It is the container, which in its preferred form is a glass bottle of common type, having a shouldered neck 2, with a full-open, relatively capacious throat, through which the bottle may be freely supplied with its powder content 3.

55 Referring first to Fig. 2, 4 is a sleeve, preferably

of metal, having a bottom cross-wall 5 and a full-open top 6 with an outer flange 7.

The bottom wall 5 is apertured, being provided with one or more openings of relatively small size, here shown by preference as a single opening 8, the shape of which may be varied, but is shown preferably, as seen in Fig. 4, of oval contour. The outer diameter of the sleeve is substantially the same as the inner diameter of the bottle neck and the length of the sleeve is proportioned to that of the neck-throat, so that when said sleeve is slipped down into the neck to a frictionally tight fit with its flange 7 resting upon the top of the neck and limiting its insertion, said sleeve by reason of its apertured bottom wall 5, presents in 10 the bottle-throat a diaphragm control well down within the neck, and restricting by its opening 8, the flow of the powder to the proper modicum when the bottle is tipped.

Referring now to Fig. 3, it will be seen that the 20 dispensing device of Fig. 2 is upside-down, that is to say its apertured diaphragm 5, which in Fig. 2 is the bottom wall, is now at the top, and its open end 6, which in said Fig. 2 is at the top, is now at the bottom; in short the sleeve 4 is 25 merely reversed end for end, the only structural change being that the penetration limiting flange 7 remains at the top being carried by the diaphragm end 5 instead of by the open end 6.

9 is a flat-top cap, preferably a screw-cap, of 30 usual type adapted for closing the bottle, when not in use. For use of the powder, the cap 9 is removed. The bottle is then tipped, and the restricted flow passes freely out.

It will be especially noted that the sleeve 4 35 in both the positional arrangements of Figs. 2 and 3 is a split sleeve as indicated at 10. The purpose and effect of thus splitting the sleeve will now be made clear.

Glass bottles for powder dispensing containers 40 of this class, while desirable for many reasons, both commercial and esthetic, present difficulties which have hitherto restricted or prevented their use. As bearing upon the invention herein, the following should be noted. Reducing stoppers in 45 the form of apertured corks are usually resorted to for the sake of frictional security. These commonly are supplemented by outer closures usually projecting more or less inconveniently and unsightly from the top. Moreover, for the 50 sake of fixity, the corks have to be so tightly fitted that they are practically permanent. Thus their easy removal for refilling the bottle or for any after-use, is out of the question.

Another difficulty which from experience I 55

have found outstanding in using metal sleeves as dispensing controllers in glass bottles, arises from the fact that glass and metal have different coefficients of temperature expansion and contraction, which difference tends to, and often does, result in breaking the bottle neck. This is true no matter how mathematically perfect the cylindrical character of the bottle throat, and the metal sleeve may be; but in addition, and perhaps most important, I have found that in manufacturing practice, the throats of glass bottles are seldom true circles in cross section, but depart therefrom to some extent, so that the metal sleeve, if truly cylindrical, fails to find a tight frictional fit. But the split sleeve, on account of circumferential resilience, not only guards against bottle breakage due to differences of expansion and contraction, but also accommodates itself to any irregularity in the bottle throat, and thus can be made frictionally tight and yet easily removable.

I claim:—

1. A powder-dispenser comprising in combination a glass-bottle having a neck with an open throat; a metal split sleeve seated in said throat in frictional contact throughout its length with the throat wall, said sleeve having a penetration-limiting flange resting on top of the neck, one end of said sleeve being open and the other end having an apertured, cross wall of less discharge capacity than the open end; and a cap fitted upon and covering the neck of the bottle.

2. A powder-dispenser comprising in combination a glass-bottle having a neck with an open throat; a metal split-sleeve seated in said throat

in frictional contact throughout its length with the throat wall, said sleeve having a penetration-limiting flange resting on top of the neck, the upper end of said sleeve being open, and the lower end having an apertured relatively stiff cross wall of less discharge capacity than the upper end; and a cap fitted upon and covering the neck of the bottle. 5

3. A powder-dispenser comprising in combination a glass-bottle having a neck with an open throat; a metal split-sleeve seated in said throat in frictional contact throughout its length with the throat wall, said sleeve having a penetration-limiting flange resting on top of the neck, the lower end of said sleeve being open, and the upper end having an apertured relatively stiff cross wall of less discharge capacity than the lower end; and a cap fitted upon and covering the neck of the bottle. 10

4. A powder-dispenser comprising in combination a glass-bottle having an externally-threaded neck with a full-open throat; a metal sleeve in said throat of a length proportioned to that of the neck-throat and of a diameter adapting it for readily insertable and removable frictional contact throughout its length with the throat wall, said sleeve having a penetration-limiting flange resting on the top of the neck and a full-open lower end, and having also a partially open, relatively stiff cross wall at its upper end, of less 20 discharge capacity than the full-open lower end; and a flat-top screw-cap fitted upon the neck of the bottle to lie closely upon and cover the partially open upper end of the sleeve. 25
